JOHN B. BURDETT, OF CHICAGO, ILLINOIS, ASSIGNOR TO DAVIS-BOURNONVILLE COMPANY, OF NEW YORK, N. Y., AND CHICAGO, ILLINOIS, A CORPORATION OF NEW YORK.

ELECTROLYTIC CELL.

1,107,257.

Specification of Letters Patent. Patented Aug. 18, 1914.

Application filed October 29, 1912. Serial No. 728,386.

To all whom it may concern:

Be it known that I, JOHN B. BURDETT, a citizen of the United States, residing at Chicago, county of Cook, State of Illinois, have made a certain new and useful Invention in Electrolytic Cells, of which the following is a specification.

This invention relates to electrolytic cells designed particularly for the manufacture of oxygen and hydrogen by an electrolytic decomposition of caustic alkali solution or other suitable electrolyte.

The object of the invention is to provide an electrolytic cell of the character referred to, which is simple in structure, efficient in operation, and wherein separation and separate collection of the gases evolved from the electrolytic decomposition is accomplished.

Other objects of the invention will appear more fully hereinafter.

The invention consists substantially in the construction, combination and arrangement of parts, all as will be more fully herein-after set forth, as shown in the accompanying drawings, and finally pointed out in the appended claims.

Referring to the accompanying drawings, and to the various views and reference signs appearing thereon:—Figure 1 is a view in vertical section showing an electrolytic cell embodying the principles of my invention. Fig. 2 is a view in section on the line 2—2 Fig. 1, looking in the direction of the arrows. Fig. 3 is a broken detail view in section on a plane at right angles to the plane of section of Fig. 2.

In the commercial manufacture of oxygen and hydrogen caustic alkali or other suitable solution is subjected to the decomposing action of an electric current whereby the solution is decomposed into its component gases. For commercial use it is exceedingly desirable to secure as complete a separation as possible of the gases evolved by the electrolytic action, so as to produce the oxygen and the hydrogen separately in as pure condition as can be attained. Moreover, during the decomposing action any intermingling or mixture of the oxygen and hydrogen gases in the relative proportion thereof required to form water is exceedingly dangerous since such a mixture is highly explosive as it is well known. For this reason it is highly necessary to prevent any possible in-

termingling of the generated gases resulting from the decomposition or electrolytic action.

In accomplishing the electrolytic decomposition of the solution in the manufacture of oxygen and hydrogen, in accordance with my invention, suitable electrodes are immersed in the electrolyte, and to a depth sufficient to enable the superincumbent weight or head of the liquid to serve to prevent the gas evolved at one of a pair of electrodes from being carried along by the decomposing action of the electric current to the other electrode of the pair, so as to become intermingled or mixed with the gas generated or evolved from the other electrode.

In accordance with the principles of my invention, I propose to employ inverted bells to inclose or partially inclose the electrode plates, and to suspend the inverted bells and electrode plates within the cell vessel to a depth sufficient for the hydrostatic pressure, or head of the electrolyte to accomplish the function of preventing the evolved gases from becoming intermingled during the decomposing or electrolytic action. I also propose to widen the mouths of the bells so as to insure the entrance of the evolved gas into the bell, the evolved gases thus being separately collected.

Referring to the drawings, reference letter A, designates the cell container or vessel, and which is provided with a top or cover B, from which is suspended a carrying bracket C. Reference letter D, designates the inverted bell or gas collector element, one being provided for each electrode plate. The bell receivers D, are provided with lugs E, at the ends thereof, and these lugs are received and supported upon the horizontal portion of the supporting brackets C, as clearly shown in the drawings. If desired, and preferably, a strip of hard rubber or other insulating material F, may be interposed between the lugs E, and the horizontal portions of the supporting brackets C. This arrangement provides a very simple and efficient means for supporting and suspending the bell-shaped collectors and the electrode plates within the vessel A, of the cell. An electrode plate G, extends up partially into the inverted bell receiver D, and at its upper edge is suitably connected

to an electrode rod or circuit terminal pole J, as clearly shown in the drawings, and from which suitable circuit connections are made for the current employed to accomplish the electrolytic decomposition of the electrolyte.

The pole J, extends through the bell D, or an opening through the closed upper side thereof, and is inclosed within a tube K. 5 Pipes L, communicate with the bells and serve to collect the gases and to conduct the same to any suitable receiver therefor. The tubes K and pipes L, extend through openings in the closed upper side of the bell. 10 The bell is inverted with its closed side uppermost. At its lower edge or mouth the edges of the walls of the bells are flared or enlarged. A convenient arrangement is shown wherein the lower edges of the bell 15 are beveled as shown at M. The electrode plate G extends below the lower beveled edges of bell D, and into the electrolyte, which is to be decomposed.

In the operation of the cell a current of 20 electricity is supplied to the element or electrode plate G, and in passing through the electrolyte from one plate to the other the electrolyte is decomposed and resolved into its constituent gases. One gas, as oxygen, 25 for instance, collects in the cell D of one of the electrode plates, while the other gas, as hydrogen, is collected in the next, adjacent bell. It has been found that the gases form and collect in the vicinity of or on the surface of the plates. The gas will rise along 30 the sides or surfaces of the plates and is collected in the inverted bells D, which inclose the plates. By beveling the lower edges of the bells, or otherwise enlarging or flaring the receiving mouth thereof, I am enabled to 35 secure a better separation of the gases and to insure the efficient collection of each gas separately within its own bell member D. As above explained the entire cell element is 40 immersed in the electrolyte to a sufficient depth for the head or weight of the superincumbent electrolyte to form a hydrostatic head or pressure which resists the tendency of the 45 gases to rise through the electrolyte to the 50 surface or from being carried along through the electrolyte from one plate to the next adjacent plate.

It will be understood, of course, that any suitable or convenient means for insulating 55 the tubes K and L, and electrode poles or rods J, from the bell D may be employed. It will also be understood that any suitable or convenient means for connecting the poles J, to their respective electrode plates G, may 60 be adopted.

In order to still further insure an efficient 65 separation of the evolved gases, adjacent bells containing the electrodes G, may be separated by intermediate bells containing 70 separating aprons H.

It will be understood that as many cell elements, each comprising an electrode plate, its connecting rod or pole J, tube K, inverted cell member D, and pipe L, may be employed, as desired in order to make up a 75 complete cell. In these respects my invention is not to be limited or restricted.

It will also be understood that many variations and changes in the details of construction and arrangement may readily occur to persons skilled in the art and still fall within the spirit and scope of my invention as defined in the claims. I do not desire to be limited or restricted, therefore, to the exact details shown and described.

Having now set forth the object and nature of my invention, and a construction embodying the principles thereof, which I claim as new and useful and of my own invention, and desire to secure by Letters Patent of the United States, is:—

1. In an electrolytic cell, a vessel to contain the electrolyte, a top or cover therefor, a support carried by the top or cover and depending into said vessel, an inverted bell 90 having a lug at the side thereof, said lug resting upon said support, whereby said bell is suspended from said support and is immersed in the electrolyte contained therein to a depth sufficient for the hydrostatic head 95 or pressure of the electrolyte to prevent intermingling of the evolved gases, an electrode plate positioned within said inverted bell, and a gas delivery pipe communicating with said bell.

2. In an electrolytic cell, a vessel to contain the electrolyte, a supporting member depending into said vessel, inverted bells each having a lug at the side thereof, said lugs resting on said supporting member 105 whereby said bells are suspended from said member and are immersed in the electrolyte to a depth sufficient for the hydrostatic head or pressure of the electrolyte to prevent intermingling of the evolved gases, an electrode plate positioned within each bell and a gas delivery pipe communicating with each bell.

3. In an electrolytic cell, a vessel to contain the electrolyte, a support depending 115 into said vessel, inverted bells suspended from said support, electrode plates arranged within said bells and extending into the electrolyte a depth sufficient to utilize the hydrostatic head or pressure of the electrolyte to prevent intermingling of the evolved gases, circuit terminal rods or poles connected to said plates and pipe connections communicating with said bells, the open mouths of the inverted bells being beveled.

4. In an electrolytic cell, a vessel to contain the electrolyte, an inverted bell suspended in said vessel and immersed in the electrolyte contained therein to a depth sufficient to utilize the hydrostatic head or 130

pressure of the electrolyte to prevent the intermingling of the evolved gases, an electrode plate arranged within the inverted bell, and a gas delivery pipe communicating with said bell.

In testimony whereof I have hereunto set my hand in the presence of the subscribing

witnesses, on this 12th day of October, A. D., 1912.

JOHN B. BURDETT.
